(57) **CLAIM**

The ornamental design for a mobile power charger, as shown and described.

DESCRIPTION

FIG. 1 is a front view of a mobile power charger showing our new design;

FIG. 2 is a top view thereof;

FIG. 3 is a right side view thereof;

FIG. 4 is a left side view thereof;

FIG. 5 is a rear view thereof;

FIG. 6 is a bottom view thereof;

FIG. 7 is a front perspective view thereof;

FIG. 8 is a rear perspective view thereof; and,

FIG. 9 is a perspective view of thereof, shown in an environment of use with a portable solar panel.

In the FIGS. 1-9, the broken lines illustrate portions of the mobile power charger that form no part of the claimed design.
